UNITED STATES PATENT OFFICE.

FREDERICK L. NAY, OF VACAVILLE, CALIFORNIA.

AUTOMATIC CHANGE-MAKING MACHINE.

1,017,447.

Specification of Letters Patent. Patented Feb. 13, 1912.

Application filed November 28, 1910. Serial No. 594,470.

To all whom it may concern:

Be it known that I, FREDERICK L. NAY, a citizen of the United States, residing at Vacaville, in the county of Solano and State of California, have invented new and useful Improvements in Automatic Change-Making Machines, of which the following is a specification.

My invention relates to change making machines, and especially to machines for making change automatically by simply pressing a key or keys indicative of the amount received, and pressing another key or keys indicative of the amount of sale or purchase.

The invention consists of the parts and the construction and combination of parts as hereinafter more fully described and claimed, having reference to the accompanying drawings, in which—

Figure 1 is a perspective view of the apparatus with portions broken away to show certain parts of the internal mechanism. Fig. 2 is a plan view in section approximately on line $x-x$ of Fig. 4, representing the selective mechanism with certain parts omitted. Fig. 3 is a front elevation in section approximately on line $y-y$ of Fig. 4, with a portion of the inside structure broken away to show a coin magazine. Fig. 4 is an end elevation in section approximately on line $w-w$ of Fig. 3, showing among other things the operating lever, means for retarding the action of the coin delivery. Fig. 5 is a perspective showing a detail of the valve mechanism for controlling the discharge of the individual coins from a magazine. Fig. 6 is a detail of the lock for the operating lever. Fig. 7 is a perspective view representing the selective mechanisms for controlling the coin discharged from a single magazine. Fig. 8 is a detail in partial section of the semaphore re-setting levers. Fig. 9 is a diagrammatic plan view of the selective mechanism indicative of the amount of purchase. Fig. 10 is a plan view of the means for automatically restoring the several selective mechanisms to initial position.

50 A represents a suitable containing cabinet which may be of any appropriate size or design, and made of any desired material. This cabinet or casing houses all the opera-

tive parts of the device, except the keys and levers necessary to be acted on directly by the operator for producing the desired results.

When the device is set up and ready for use the only working parts exposed, are, the setting key 2, (Fig. 1), the releasing key 3, the upper bank of keys 4 representing the "amount received" the lower bank of keys 5 representing the "amount of sale" or "purchase" keys; and the operating handle 6 by which the difference between the sum total of the keys 4 which are pushed in and the sum total of the keys 5 which are pushed in, is paid out.

The amount of coin in the machine for change making purposes, is contained in a series of magazines 7 which are of appropriate shape, and sufficiently numerous, and of sufficient capacity to meet the requirements of the machine. These magazines are preferably constructed, as shown in Figs. 1, 7 5 and 7 of the drawings, and particularly in Fig. 1, to hold the coins on edge, one above the other, without any danger of the coins overlapping. These magazines may extend upward and be protected by a heavy glass front, through which the condition of the coin supply in the magazines may be readily discerned. The magazines are open at the top so as to be easily replenished from time to time, and the discharge of the coins from these magazines is accomplished by certain selective mechanisms controlled by the keys or push buttons 4—5, and which selective mechanisms form essential features of the present invention.

By reference to Fig. 1 it will be noted that there are two banks of keys 4—5; the bank 4 as before stated, indicating the "amount received", and the bank 5 indicating the "amount of sale" or the "amount of purchase". There may be any number of keys in each bank and they will be appropriately designated according to the national monetary system, and according to the amounts of change to be made. The keys 4 of the "cash received" series run progressively from 5¢ to \$20, thus; "5¢", "10¢", "25¢", "50¢", "\$1", "\$2", "\$3", "\$4", "\$5", "\$10", "\$20". The lower bank of keys 5 representing the "amount of sale" runs progressively thus; "10¢", "10¢", "5¢",

"50¢", "\$1", "\$1", "\$2", "\$5", "\$10", There are two 10¢ keys in the amount of sale bank at the left, and the 5¢ key follows third. This is merely for the matter of simplicity in the internal working parts of the machine and for making change. There are also two \$1 keys, on account of the condition arising in the actual making of change.

While this machine is not designed to pay larger amounts than \$20 nor smaller amounts than 5¢, it is manifest that the device can be readily adapted to any minimum or maximum amount. The magazines 7 are adapted to have their coin controlling devices operated upon by one or more of either bank of keys 4—5. As shown in Fig. 1, these magazines progress from left to right, as follows: "10¢", "5¢", "5¢", "5¢", "25¢", "50¢", "\$1", "\$1", "\$1", "\$1", "\$5", "\$10". The magazines necessarily correspond to the denominations of coins minted, and there are a plurality of 5¢ magazines and of \$1 magazines, because of the frequency with which such coins are paid out, and a single magazine for either denomination would not hold enough coins in the first place, and in the second place a plurality of magazines for these denominations is necessary to meet the exigencies in making change. For example, the purchaser is handed \$5; the amount of the purchase comes to 30¢, if all the change is to be delivered to the purchaser by a single actuation of the machine, it is necessary for the machine to deliver four \$1 pieces, a 50¢ piece, a 10¢ piece, and two nickels, or \$4.70. This of course requires four \$1 magazines to deliver the \$4. The manner in which the delivery of the change is effected will be more readily understood later. As the mechanisms by which the coin is delivered from each magazine is the same for all the magazines, it will be manifest that the description of the connections between one of the upper banks of keys 4 and a magazine and one of the lower bank of keys 5 with the particular magazine will suffice for purposes of illustration.

By reference to Fig. 7 especially, a clear understanding of the connection between the keys 4—5 and the magazines 7 can easily be had. As shown in said Fig. 7, each key 4 is attached to an angular stem 8 mounted for reciprocation in suitable guides in the frame. The stem 8 has a shoulder 8' adapted when the key 4 is pushed in, to engage an angular arm 9 on a rock shaft 10. The other end of this rock shaft 10 has an angular lever arm 11 which is loosely connected by a link 12 with a spring-activated hinged frame 13. The frame 13 is hinged to the casing at 14 and has a downwardly extending projection 15 arranged in the path of an angular arm 16 of a rock shaft 17. This shaft 17 has another angular arm 18 which is arranged in

the path of a hump or shoulder 19 on the angular stem 20 of a lower key 5. Thus it will be seen that pushing in on lever 4 will engage the arm 9 and cause the shaft 10 and its angular arm 11 to rock. The loose connection 12, however, with the frame 13 permits a movement of the parts 9—10 and 11 without any movement of its corresponding frame 13, but this particular frame 13, which is connected with this particular key 4, will be rocked when the lower key 5 is pushed in. As will be particularly explained shortly, every other frame 13 which lies to the right of the particular lever arm 11, which has been acted upon, will be rocked to the left by reason of certain link connections 21 between these several frames to the right and this particular lever arm 11. Consideration of this matter of rocking these other arms must temporarily be deferred until the mechanism shown in Fig. 7 is clearly explained and the parts which are directly under the control of any two keys 4—5, fully understood.

By pushing in on key 5 in Fig. 7, it will be manifest that when the shoulder 19 of the stem 20 hits the angular lever arm 18, the other angular lever arm 16 will be rocked to the left to engage the projection 15 of the frame 13 and rock the same to the left against the tension of the spring 22. The lower horizontal side of the wire frame 13 extends forward and is provided with an eye 23 which surrounds and forms a support and guide for a pin 24 which is hinged to the upright arm 25 of an angular lever 26 which is fulcrumed at 27. The lever 26 carries a projection 28, which is normally arranged in the path of the coin 29 in a magazine 7.

The lever 26 and projection 28 form one member of the valve mechanism for controlling the discharge singly of the coins from the magazine. The other member of this valve mechanism consists of the angular lever 30 fulcrumed at 31 and having a projection 32 normally out of the path of the coin 29 but operable alternately with the projection 28. When projection 32 is pushed in, it engages in the perforation 33 in the magazine to intercept the coin after the same has been dropped by the outward withdrawal of the projection 28. The other end of the lever 30 has an angular arm 34 arranged in the path of the angular arm 25 of the lever 26. A spring 35 acts normally to hold the arm 34 in operative contact with the arm 25. By thus employing a lever 26 of the first class and a lever 30 of the third class and arranging them in the manner shown, I produce a simultaneous actuation of both levers, but in opposite directions, whenever the pin 24 is pushed in to rock the lever arm 25. The valve members or projections 28—32 are so spaced from each

- other, that as the member 28 is moved outward from beneath the coin the member 32 is moved inward to intercept the coin and the part 28 moving in again to intercept the next succeeding coin without interfering with the coin which is now temporarily supported on a lower valve member 32; the interception of the second coin by the valve member 28 always taking place before the final release of the first coin by the valve 32. Neither of the keys 4-5 operates to release the coin. All that the key 5 does as shown in Fig. 7 is to rock the pivot pin 24 on its fulcrum on the arm 25 of lever 26. As will be shortly shown, this rocking of the pivot pin 24 simply acts to carry this pin out of the path of adjustable pressers 36, (Figs. 5-1 and 4) which are carried on the hinged actuating bar 37.
- Having understood the operation of the parts as shown in Fig. 7, the nature of the invention and the operation of the device can be more readily understood. There is a spring actuated frame 13 similar to that shown in Fig. 7 arranged in corresponding relation with each magazine, as indicated in plan view in Fig. 2, and diagrammatically in Fig. 9. These several frames 13 as shown in Figs. 9 and 2 are each capable of a limited independent rocking movement, but they are all connected together in such fashion that they may be all simultaneously rocked to the left against the tension of their springs 22 to carry all the pins 24 out of the path of the pressers 36 mounted on the actuating bar 37. As is shown in Fig. 9 the several frames 13 are connected with a cord or chain 38 which passes over a direction pulley 39 and connects with a lever 40, Fig. 1. A spring 41 having a tension greater than the aggregate tension of all the small springs 22 acts on the lever and chain 38 to draw the frames 13 normally to the left and carry the pins 24 out of the path of the pressers 36.
- The lever 40 is fulcrumed at 42 and is operated on by the set key 2. By pushing down on the key 2, lever 40 is rocked to relieve the tension on the springs 22 and allow all the pins 24 to be brought into line with the pressers 36. Thus it will be seen that if the presser bar 37 is now rocked to cause the pressers 36 to impinge on and press in the several pins 24, the valve devices 28-32 will be operated as it has just been explained in connection with Fig. 7. The function of the keys 4-5 however, is to cut out certain of the pins 24 so that when the actuating bar 37 is rocked, only a certain limited number of the pins 24 and magazines will be acted upon. This cutting out of certain magazines is accomplished by turning the pins 24 of those magazines to one side of the path of their respective pressers 36, by connecting certain of the upright lever-arms 11, Fig. 7, with certain other similar lever arms in the series, as is better shown in Fig. 2 and Fig. 9.
- As is shown in Fig. 7 a link 21 extends to the right and terminates in an elongated eye 21^a, in which a succeeding upright lever arm 11^a is operable. Also in Fig. 7 is shown a link 21^b which has a similar eye 21^b in which the upright 11 is engaged; and this link 21^b extends to the left and connects with the chain 38, which connects with the lever 42, Fig. 1. The purpose of the elongated eyes 21^a is to permit a movement of any one of the oscillating arms 11, 11^a, &c., without affecting the mechanisms which lie to the left of that particular arm. Thus while pushing in on the key 4 of Fig. 7, will rock its particular arm 11 and pull over on link 21 and correspondingly rock all the frames 13 which are to the right, it will not effect any actuation of the frames which may be to the left. The purpose of this will be more apparent when we come to describe the complete operation of the machine and the way in which the actual making of change is done.
- As is shown in Fig. 1 when the setting key 2 is pushed down, the lever 40 will be engaged by a spring actuated latch 44 and held in that position, and with all the pins 24 in line with the pressers 36, the machine is then ready to make change. To illustrate, if \$1 has been handed the operator, which amount we will call the "amount received", and the purchase has amounted to 75¢, the operator will push in the \$1 key in the upper 4-series. This \$1 key by reason of its link connections 21 with the rocker-arms 11, &c., of the keys marked "\$3", "\$1", "50", "\$10", "\$20", will rock the frames 13 of those last-named keys to the left and carry their pins 24 out of the path of their corresponding pressers 36. It should be said that while there are four \$1 magazines shown in Fig. 1, three of these correspond respectively to the \$2, \$3 and \$4 keys of series 4. This is because there are no such coins as \$2, \$3 and \$4 pieces, and this machine is designed only to pay coin; at the same time a purchaser might hand any amount of money, \$3, \$3.50, \$7 or \$9.25, &c., in payment of a purchase, expecting change back to the amount of the difference between the amount handed to the operator and the amount of the purchase. Continuing the above illustration of supposing that \$1 had been handed the operator and the purchase was 75¢; a pushing in of the \$1 key of the 4 series cuts out all the magazines above \$1 and including the \$1 magazines, so that the most that the machine can pay is the amount represented by the headings of the several magazines to the left of the \$1 magazine corresponding to the \$1 No. 4 key. It will be observed that the sum total of all these remaining headings

amounts to just \$1. (All the keys 4 and 5 are pressed normally outward away from their respective levers 9—18 by means of the springs 4^a. When any key is pushed in it is temporarily held in against the tension of its spring 4^a by means of a spring-actuated rocking latch 4^b.) Having pushed in on the \$1 No. 4 key, and the same having been locked by its catch 4^b, the operator 10 next pushes in on certain of the No. 5 keys to represent a total of 75¢, the amount of the purchase. Ordinarily this 75¢ purchase would be indicated by the 50¢ key and the 25¢ key. Pushing in on the 50¢ and 25¢ 15 keys of the No. 5 series, effects a further diminution of the number of pins 24, which are in line with the pressers 36. As has just been said when the \$1 of the amount received—bank of keys 4 was pushed in, there 20 remained only \$1's worth of pins 24 in line with their pressers 36; consequently, if the actuating bar 37 was rocked at that moment, only \$1 in change would be delivered from the magazines. When the operator pushed 25 in on the 50¢ and 25¢ keys of the No. 5 series or amount of sale bank, two more pins 24 were carried out of the path of the actuators 36, leaving only 25¢ in change to be paid by the machine. (Of course instead 30 of pushing in the 25¢ key of the No. 5 bank, the operator could have pushed in the two 10¢ keys and the 5¢ key of this same bank with the same result.) Having thus pushed in the proper keys of the two banks to represent respectively the "amount received" 35 and the "amount of sale", the change is paid out by the machine by the operator taking hold of the handle 6, which is connected to the actuating lever 45, and rocking this lever to cause the actuators 36 to 40 impinge on those pins 24 which are still in line with the actuators. As shown in Fig. 1 the lever 45 is rigidly connected to the bar 37, and the spring 46 acts to hold the actuators 36 in normally inoperative position 45 with respect to the pins 24. The lever 45 has a projecting arm 47 to which the spring 46 connects. The lever 45 is engageable by a spring catch 48 to prevent the accidental 50 or unauthorized operation of the machine. In order to operate the lever 45 it requires a slight outward pull on the handle 6, which latter runs in the segmental slot 49 to release the lever 45 from the catch 48 and, al- 55 low the lever 45 to be pushed back and rock the actuating bar 37. The movement of the pivoted catch 48 is limited, and the actuating lever 45 is springy enough to allow it to be released from the catch when 60 the handle 6 is pulled outward, as just explained.

If in making the change the operator has pushed in the wrong keys, the latter together with all the hinged frames 13 can be thrown 65 out of gear instantly, by actuating the re-

lease key 3, Fig. 1. This release key has its stem connected with the bar 50, Figs. 3 and 10, which is suitably mounted on swinging arms 50; for lengthwise reciprocation, and has a series of projections 51 corresponding each to a latch-member 4^a. The spring 52, Fig. 3 and Fig. 10, acts on this release bar 50 to throw it normally to the left out of interference with the latch operations of the latches 4^a. Whenever a key as 4 or 5 Fig. 7, is pushed in, the spring-actuated-latch 4^a will swing in behind the shoulder 8^a or 20^a of the respective stems 8—20 and hold the key in. When the latches 4^a are in this position, they abut against the projections 51 on the release bar 50. Consequently when bar 50 is pushed to the right, it will carry the latches 4^a out of engagement with the key stems and allow the keys to assume their normal outwardly pressed position. The releasing bar 50 is also adapted to be operated automatically to release the keys 4 and 5 by suitable connections with the operating lever 45. As here shown the lever 45 is connected by a normally slack chain 52 with a bell-crank-lever 53 fulcrumed at 54 and connected by a link 55 with a lever 56. (Fig. 10).

The lever 56 is fulcrumed between its ends and carries a weight 57 at one end. A spring 58 acts on the lever 56 to press the weight normally into contact with the left hand end of the releasing bar 50. When the lever 45 is moved back to rock the actuating bar 37, the bell-crank-lever 53 is rocked and one arm is carried back until it is engaged by a dog 59, Fig. 4. At the same time the lever 56 is rocked to carry the weight 57 away from the actuating bar 50. The latch 59 retains its hold on the lever 53 until nearly 100 the completion of the return movement of the actuating lever 45. About that time, and after the change has been released from the magazines, a rod 60 carried by the arm 47 of lever 45 depresses the rear end of the 105 latch 59 and releases the bell-crank 53, whereupon the spring 58 causes the weight 57 to strike a sharp blow on the releasing bar 50 and drive it to the right so that all the catches 4^a will be released. At the same 110 time the catch 44 (Figs. 1—3—10) which holds the setting key 2 down is released from its hold on lever 40 by connections 44' with bar 50.

In order to insure a full swing of the actuating lever 45 and give positiveness of action to the machine, the lever 45 carries a spring-actuated pawl 61 as shown in Fig. 6, which is adapted to ride free in one direction over a stationary rack 62 when the actuating lever 45 is rocked in one direction and to ride free in the other direction over this rack when the lever is rocked in the other direction. After the lever has been started to move in one direction it cannot 115

be returned until it reaches the full limit of its stroke in that direction.

When the coins are released from the magazines by the engagement of the pressers 36 with respective pins 24, which operation is effected by pushing back on the actuating lever 45 as just described, the coins strike on spring-actuated-flap-members 64 (Figs. 5 and 8) arranged in the path of the falling coins, and these flap-members actuate corresponding semaphores 65, Fig. 5, which semaphores correctly represent the amount of money actually paid by the machine. These semaphores slide in suitable guides arranged just behind or in front of their respective magazines.

As is shown in Figs. 5 and 8 the flap-members 64 are mounted on a common fulcrum shaft 66, and each flap-member 64 has an arm 66' connecting with a spring latch plate 67. Each semaphore 65 is adapted to be normally projected upward by a spring 68, and each semaphore carries an angular piece 69 at its lower end to which is attached one end of a cord 70; the other end of this cord is connected to a spring-roller 71. This roller or drum 71, Figs. 3 and 4, has one end of a chain 72 wrapped around it, and the other end of this chain is connected by a link 73 with the arm 47 of the actuating lever 45. Thus it will be seen that when the actuating lever 45 is pushed back to make change, the spring roller 71 is turned against the tension of its spring 75 to wind up the several cords 70 and pull down the semaphores until the angular pieces 69 on the semaphores are caught over the end of the spring-catch-plates 67, provided any of these spring-catch-plates 67 have been lifted by the actuation of a valve or flap 64 on the falling of a coin. When the coin strikes a flap, it pulls out on the lower spring end of one of these spring-catch-plates and allows the angular semaphore projection 69 to slide up behind it and cause its semaphore 65 to show above the top of the magazines.

The coins which are released from the magazines are delivered from the machine by any suitable means. I prefer to use a draper or endless belt 75', Figs. 3-4, running over the drums 76-77 and to give this draper an intermittent rotative movement through suitable connections with the actuating lever 45. As here shown the drum 76 has a cord 77' wrapped around it in one direction with the end of this cord or chain connected with a suitably anchored spring 78. A chain or cord 79 is wrapped around the shaft of the drum 76 in the opposite direction, and this chain passes around suitable direction pulleys 80-81 and connects to the actuating lever 45. When the actuating lever is pushed back to pay out change, the chain 79 turns the draper backward against the tension of the spring 78.

With the draper thus on tension it is held in that position temporarily by a suitable brake mechanism consisting, as shown in Fig. 4, of an angular lever 82 having a rubber or like soft head 83 which is adapted when the end of the lever is dropped to contact with the head of the drum and temporarily prevent rotation of the drum under impulse of the spring 78. The other end of the lever 82 has a loose connection 84 with a cross-head of a piston 85 which acts in an air cylinder 86. This cross-head 85 is acted on by a spring 87 which normally presses the piston 85 inward into the cylinder 86. The construction of this cylinder is such that the piston can move freely outward in the cylinder, but the inward movement of the piston under tension of the spring 87 is retarded by the compression of the air in the cylinder. This construction of pneumatic or fluid controlled device is so well known as not to need further detail description. The piston 85 is also connected by a slack chain 88 with the actuating lever 45. When the lever 45 is pushed back to cause the machine to pay out change, the piston 85 is pulled outward when the slack of the chain 88 is taken up. This releases the slack on the connections 84 of the piston with the brake 82 and allows the latter under the tension of its spring 89 to fall so that the head 83 engages the drum 76, thus locking the drum against movement in one direction as has been explained. When the actuating lever 45 moves back again to initial position and after the change has dropped on to the draper, the piston 85 is allowed to retreat into the cylinder 86 as soon as the chain 88 slackens. It will be readily understood that with the draper turned back and with the cord 77 wound up and the spring 78 on tension, that the moment that the brake 82 is released, the draper will travel in the direction of the pay chute 90 and deliver all the coins at once into this chute or pocket, where they can be handed by the operator to the customer.

In operation assume the machine to be in normal position ready to make change: The operator is handed \$1 in payment of a 75¢ purchase. He first pushes down on key 2 to "set" the machine; *i. e.* to rock all the frames 13 and place the pins 24 in line with their respective actuators 36. He next pushes in the \$1 key of the amount received series 4. This key by reason of its connecting links 21 with the rocker arms 11^a-11^b, &c., of the No. 4 amount received keys, marked \$3, \$4, \$5, \$10, \$20, will rock the frames 13 of these last named keys to the left and carry their pins 24 out of the path of their corresponding actuators 36 on bar 37. When the "\$1" key above, was pushed in, it was engaged and held in by

the catch 4^a. Next the operator pushes in the keys of the amount of sale or "purchase" series 5, to the aggregate of the amount of sale. Ordinarily he pushes in 5 the "50¢" key and the "25¢" key of the amount of purchase series #5, and these keys are held in by their respective catches 4^b. (If for any reason he has made a mistake in pushing in any of the keys of either 10 series he simply throws the machine out of gear and places all the parts in initial position by pushing on the releasing key 3 which operates the release bar 50 to trip the latches 4^a, or 4^b or both according as both 15 sets of keys 4—5 have been acted on, and to release the latch 44 to allow all the keys to return to normal. He then begins over again.) Pushing in on the "50¢" and "25¢" 20 keys of the #5 "purchase" series as above described, cuts out the corresponding pins 24 by which delivery from the "50¢" and "25¢" magazines is controlled.

While the "amount received" keys 4 are coupled up in accordance with their several 25 monetary values so that under no circumstances can a sum be paid out in excess of the amount represented by the punched keys of this series, the "amount of purchase" keys are adapted individually in most instances to act only on a single actuator pin 24 and so cut out an individual magazine: each time a key 5 is punched it subtracts just so much from the amount represented by the punched "amount received" keys 4. The 30 operator next takes hold of the handle 6 of the actuating lever 45, pulls it out a little so as to disengage the latch 48 and then pushes back on the lever to rock the actuating bar 37 and cause the actuators 36 to engage such of the pins 24 as have not been previously moved out of line with the actuators. These remaining pins 24 which are now acted on are only those belonging to the "10¢" magazine and the three "5¢" magazines and as only a single coin can be delivered from any magazine by one actuation of lever 45, it is manifest that only 25¢ will be paid from these four magazines. The actuation of lever 45 to rock the bar 37 causes the pins 24 of these four magazines to move back and to operate the valve levers 26—30 (Figs. 7 and 5): when valve members 28—32 reverse their positions shown in Fig. 7 and assume their position indicated in Fig. 5, the coin drops onto valve member 32. When the pressure on the pin 24 Fig. 5 is relieved, the members 32—28 change positions again back to that of Fig. 7, and the coin drops onto the draper 75. Meanwhile 60 the draper has been turned to put its spring 78 on tension and locked temporarily in that position by the brake 82—83. When the lever 45 comes back to initial position and after sufficient time has elapsed for the coins 65 to fall from their magazines onto the draper,

the brake is released and the draper runs forward to deposit all the coins which are on it, into the pocket 90. The amount so deposited is the correct change of the customer, providing the keys 4—5 have been punched correctly. In the return movement of the operating lever 45 to initial position the releasing bar 50 is operated to release the several latches 4^a, 4^b and 44, to allow the several keys 4—5—2 to resume their normal position. The hammer 57 (Fig. 10) may in the act of operating the bar 50, actuate a bell 91 by means of the clapper 92 carried by lever 56, for the purpose of giving an audible signal to show the operation of or tampering with the machine. The coins when they are dropped from the magazines onto the draper, strike the flaps 64 and release the semaphores 65 of those magazines paying out coin. Thus in the illustration above of paying 25¢ 85 in change the "10¢" semaphore and the three "5¢" semaphores are elevated to show to the customer and the operator just the amount of change actually paid out. These semaphores are depressed again into inoperative position on the return of the actuating lever 45 by the winding up of the cords 70 on the roller 71 as previously described.

Among the favorable features of this machine are to be noted the following: The 95 paying of change being mechanical the machine cannot pay wrong if the amounts received and amount of purchase are punched correctly. The machine cannot be operated at all unless the handle 6 is first pulled to the right which unlocks lever 45. The machine will not pay change unless the setting key 2 is punched, but the handle will work and ring the bell. The machine indicates the amount of change actually paid out, and not 100 the amount it should pay, unless it actually pays that amount. If it pays short, it indicates short as seen by the semaphores; and if it pays over, it registers over. Thus the actual amount received by the customer is 110 accurately told by the machine, which is an important feature should there be a dispute over change. Change for any denomination can be made, within the limits of the machine by simply pushing the button in the 115 amount received bank, and the setting key 2, and then working the lever 45. Amounts of 10¢—25¢—50¢—\$1—\$5—\$10 and \$20 must be punched by their corresponding amount received key; but amounts for which there 120 is no single key may be punched by any combination of keys, viz: If \$7 is the amount to be punched, keys \$5 and \$2 or keys \$4 and \$3; if \$8 is the amount, keys \$5, \$2 and \$1, or keys \$5 and \$3 may be used. Change can be paid out in the largest denomination possible, or may be paid out in small denomination at the will of the operator. If by chance a piece of money should stick in machine, it registers that amount short, which 130

can be seen at a glance by reference to the semaphores. Money when received can either be dropped in slots in the magazines or into a drawer as 93 at the bottom of machine through slot 94 (Fig. 1). If it is noticed that the machine is getting short of a particular denomination money as received, can be dropped into that magazine. At night when it is desired to remove money from the machine it can be done in a second by pulling a lever 95 which rocks a bar 96, Figs. 4—5—7, on which all the valve levers 26—30 are mounted. This has the effect of removing all the valve members 28—32 out of the path of the incumbent columns of coins so that all the money in the magazines falls on to the draper. Mistakes can not be made in counting out change, or reckoning change by the machine, provided the right keys are punched. If the wrong keys are accidentally punched, they can be released by the key 3 especially designed for that purpose; whereupon the right ones can be punched over again.

25 It is possible that various changes and modifications may be made in the invention without departing from the principle thereof.

Having thus described my invention, what I claim and desire to secure by Letters Patent, is—

1. In a change making machine, a coin magazine, and means for delivering the coin therefrom, said means including a lever having one end interposable in the path of the coin, a horizontally disposed transversely rockable pin carried by the other end of the lever, and an actuator alinable with the pin to operate the lever and release the coin.

2. In a change making machine, a coin magazine, and means for delivering the coin therefrom, said means including a lever having one end interposable in the path of the coin, a horizontally disposed transversely rockable pin carried by the other end of the lever, an actuator alinable with the pin to operate the lever and release the coin, and means for moving said pin into and out of alinement with the actuator.

3. In a change making machine, a coin magazine, and means for delivering the coin therefrom, said means including a lever having one end interposable in the path of the coin, a horizontally disposed transversely rockable pin carried by the other end of the lever, an actuator alinable with the pin to operate the lever and release the coin, and means including a push-key for moving said pin out of alinement with said actuator.

4. In a change making machine, a coin magazine, and means to control the delivery of the coin from the magazine, said means including a lever, a horizontally disposed transversely rockable and longitudinally movable member on the lever, and an actuator alinable with said rockable-member.

5. In a change making machine, a coin magazine and means for controlling the delivery of coin therefrom said means including two levers, one of which has a part interposed in the range of action of the other whereby one lever is operable by the other, said levers having rearwardly acting valve members, and means including a transversely rockable push pin carried by one lever, for operating said levers.

6. In a change making machine, a coin magazine, and means for controlling the delivery of coin therefrom, said means including two levers, one of which has a part interposed in the range of action of the other whereby one lever is operable by the other, said levers having alternately acting valve-members, an actuator, and means including a horizontally disposed transversely rockable pin carried by one of the levers and alinable with said actuator.

7. In a change making machine, a plurality of coin magazines, and means for controlling the delivery of coin therefrom, said last-named means including rockable levers associated with each magazine, one of said levers having a part extending into the range of action to the other lever actuating devices for said levers, said devices including a horizontally disposed transversely rockable pin carried by one of the levers, and means for placing one or more of said levers in inoperative position with respect to said actuating devices.

8. In a change making machine, the combination of a plurality of coin magazines, and means for controlling the delivery of coin therefrom, said means including lever-members associated with each magazine, horizontally disposed transversely rockable longitudinally movable pins carried by said lever-members, actuators with which said pins are alinable, and means including horizontally swinging frames connected to the pins for moving one or more of said pins out of alinement with their respective actuators.

9. In a change making machine, a plurality of coin magazines, a lever in connection with each magazine and controlling the delivery of coin therefrom, means including horizontally disposed transversely rockable pins; a series of actuators corresponding to said pins, means for operating the actuators, and means for placing one or more of said levers in inoperative position with respect to said actuators.

10. In a change making machine, a bank of amount-received-keys, a second bank of amount-of-purchase-keys, selective mechanism operable by said several keys, and a setting key for spacing the selective mechanism in operative position with respect to said banks of keys, and a universal bar for resetting the selective mechanism to inoperative position.

11. In a change making machine, a bank of amount-received-keys, a bank of amount-of-purchase-keys, coin magazines and selective mechanisms controlled by said several keys, said amount-received-keys coupled in accordance with their several monetary values so that the sum paid-out will not be in excess of the amount represented by the punched-keys of said series, and said amount-of-purchase-keys operative through said selective mechanisms to subtract an amount equal to the amount represented by the amount-of-purchase-keys punched in, from the punched amount-received key, and a setting key for placing the selective mechanism in operative position, with respect to said banks of keys and a universal bar for resetting the selective mechanism to inoperative position.
12. In a change making machine, a bank of amount-received-keys, a second bank of amount-of-purchase-keys, coin magazines, selective mechanisms operable by said keys, a setting key for placing said selective mechanisms in operative position with respect to said banks of keys and a universal bar for resetting the selective mechanism to inoperative position.
13. In a change making machine, a bank of amount-received-keys, a bank of amount-of-purchase-keys, a series of coin magazines, a series of actuators corresponding to said magazines, selective mechanisms operable by said actuators, a setting key for placing the selective mechanism in operative position with respect to said banks of keys and connections between the keys of said banks to place corresponding selective mechanisms into operative position with respect to said actuators and a universal bar for resetting the selective mechanism to inoperative position.
14. In a change making machine, a bank of amount-received-keys, a bank of amount-of-purchase-keys, a series of coin magazines, a universal actuator corresponding to said magazines, selective mechanisms operable by said actuator, a setting key for placing the selective mechanism in operative position with respect to said banks of keys, connections with the keys of said banks to place corresponding selective mechanisms into operative position with respect to said actuator, an operating lever connected with said actuator for operating the latter, and means for preventing said lever from swinging in one direction until it has made a full stroke in the opposite direction.
15. In a change making machine, a bank of amount-received-keys, a bank of amount-of-purchase-keys, a series of coin magazines, a series of actuators corresponding to said magazines, each of said actuators including a lever mechanism and an associated horizontally rockable push pin, selective mechanisms operable by said actuators, connections with the keys of said banks to place corresponding selective mechanisms into operative position with respect to said actuators, and means for placing individual of said pins out of operative position with their respective actuators, and a universal bar for resetting the selective mechanism to inoperative position.
16. In a change making machine, a bank of amount-received-keys, a bank of amount-of-purchase-keys, a series of coin magazines, a series of actuators corresponding to said magazines, each of said actuators including a lever mechanism and an associated horizontally rockable push pin, selective mechanisms operable by said actuators, connections with the keys of said banks to place corresponding selective mechanisms into operative position with respect to said actuators, means for placing individual of said pins out of operative position with their respective actuators, said last-named means including a push-key, and connections between the push-key and a corresponding pin, and a universal bar for resetting the selective mechanism to inoperative position.
17. In a change making machine, a bank of amount-received-keys, a bank of amount-of-purchase-keys, a series of coin magazines, a series of actuators corresponding to said magazines, selective mechanism operable by said actuators, connections with the keys of said banks to place corresponding selective mechanisms into operative position with respect to said actuators, means for placing said pins out of operative position with their respective actuators, said last-named means including a push-key, connections between the push key and a corresponding pin, a latch to hold said last-named key in depressed position, and a device to release the latch.
18. In a change making machine, a series of coin magazines, a device to control the delivery of coin from each magazine, each of said devices including a lever mechanism carrying a horizontally disposed transversely rockable and longitudinally movable pin-member, a series of actuators, means for placing all of said pins in alinement with said actuators, and means for operating the actuators.
19. In a change making machine, a series of coin magazines, a device to control the delivery of coin from each magazine, each of said devices including a lever mechanism carrying a horizontally disposed transversely rockable and longitudinally movable pin-member, a series of actuators, means for placing all of said pins in alinement with said actuators, means for operating the actuators, and means for selecting certain of said pins for removal out of operative position with respect to said actuators.

20. In a change making machine, a series of coin magazines, a device to control the delivery of coin from each magazine, each of said devices including a lever mechanism 5 carrying a horizontally disposed transversely rockable and longitudinally movable pin member, a series of actuators, a setting key, connections between said key and said pins to place them in alinement with said actuators, and means for operating said actuators. 10
21. In a change making machine, a series of coin magazines, a device to control the delivery of coin from each magazine, each of said devices carrying a rockable-pin-member, a series of actuators, a setting key, connections between said key and said pins to place them in alinement with said actuators, means for operating said actuators, and 15 means including a releasing key for throwing said pins out of operative position with respect to said actuators. 20
22. In a change making machine, a series of coin magazines, a device to control the delivery of coin from each magazine, each of said devices carrying a rockable-pin-member, a series of actuators, a setting key, connections between said key and said pins to place them in alinement with said actuators, means for operating said actuators, a bank of amount-received-keys representing values, connections between the several keys of said bank and certain of said pins, whereby the latter are moved out 25 of operative position with their respective actuators when said keys are depressed in. 30
23. In a change making machine, a series of coin magazines, a device to control the delivery of coin from each magazine, each of said devices carrying a rockable-pin-member, a series of actuators, a setting key, connections between said key and said pins to place them in alinement with said actuators, means for operating said actuators, a bank of amount-received-keys representing values, connections between the several keys of said bank and certain of said pins, whereby the latter are moved out of operative position with their respective actuators 35 when said keys are depressed in, a bank of amount-of-purchase-keys, and connections between the keys of said last-named bank and respective of said pins whereby a respective pin will be carried out of operative position with its respective actuator when one of said amount-of-purchase-keys is punched, and means including a reciprocating bar for releasing the several keys from their punched position. 40
24. In a change making machine, a series of coin magazines, a device to control the delivery of coin from each magazine, each of said devices carrying a rockable-pin-member, a series of actuators, a setting key, connections between said key and said pins to place them in alinement with said actuators, means for operating said actuators, 45 a bank of amount-received-keys representing values, connections between the several keys of said bank and certain of said pins, whereby the latter are moved out of operative position with their respective actuators when said keys are depressed in, a bank of amount-of-purchase-keys, and connections between the keys of said last-named bank and respective of said pins whereby a respective pin will be carried out of operative 50 position with its respective actuator when one of said amount-of-purchase-keys is punched. 55
25. In a change making machine, a series of coin magazines, a device to control the delivery of coin from each magazine, each of said devices carrying a rockable-pin-member, a series of actuators, a setting key, connections between said key and said pins to place them in alinement with said actuators, means for operating said actuators, a bank of amount-received-keys representing values, connections between the several keys of said bank and certain of said pins, whereby the latter are moved out of operative position with their respective actuators when said keys are depressed in, a bank of amount-of-purchase-keys, and connections between the keys of said last-named bank and respective of said pins whereby a respective pin will be carried out of operative 60 position with its respective actuator when one of said amount-of-purchase-keys is punched, and means for visibly representing the difference between the sum of the amount-received-keys which are punched and the sum of the amount-of-purchase keys which are punched. 65
26. In a change making machine, a series of coin magazines, and means for controlling the delivery of coin therefrom, said means including a series of spring-actuated-rockable frames, a series of actuators, rockable-pin-members turnable in unison with said frames, a setting key for placing said several pin-members in alinement with the actuators, and means for moving one or more of said pins out of line with said actuators. 70
27. In a change making machine, a series of coin magazines, and means for controlling the delivery of coin therefrom, said means including a series of spring-actuated-rockable-frames, a series of actuators, rockable-pin-members turnable in unison with said frames, a setting key for placing said several pin-members in alinement with the actuators, a bank of amount-received-keys representing values, connections between said keys and a plurality of said spring-actuated-frames to rock the latter on the depression of said keys, a bank of amount-of-purchase-keys, and connections between in 75 80 85 90 95 100 105 110 115 120 125 130

dividual of said latter keys and corresponding individual frames.

28. In a change making machine, a coin magazine, mechanism for controlling the delivery of the coin from the magazine, a spring actuated semaphore indicative of the value of the coins in the magazine, and means actuated by the coin for operating the semaphore, said last-named means including a flap-member disposed in the path of the coin having an arm, and a spring latch plate connected with said arm.

29. In a change making machine, a coin magazine, mechanism for controlling the delivery of the coin from the magazine, a semaphore indicative of the value of the coins in the magazine, and means actuated by the coin for operating the semaphore, said last-named means including a fulcrumed flap member arranged in the path of the coin having an arm and a spring latch plate connecting with said arm, and connections between said lever and semaphore.

25 30. In a change making machine, a coin magazine, a spring-actuated-semaphore, a device operable by the coin in the magazine, connections between said device and the semaphore to release the latter to display a signal, said connections including a rockable flap member having an arm, and a spring latch plate connecting therewith and means for replacing the semaphore in inoperative position.

35 31. In a change making machine, a coin magazine, mechanism for controlling the delivery of coin therefrom, said mechanism including a lever member associated with the magazine and a horizontally disposed, transversely rockable, longitudinally movable pin carried by the lever member, an endless-carrier on which the coin is deposited, and means for automatically moving the carrier in one direction to discharge 45 the coin.

32. In a change making machine, a coin magazine, mechanism controlling the delivery of coin therefrom, said mechanism including a lever member associated with the magazine and a horizontally disposed, transversely rockable, longitudinally movable pin carried by the lever member, an endless carrier, and means operated by the same means which controls said coin delivery mechanism, to give said carrier intermittent motion.

33. In a change making machine, a coin magazine, mechanism controlling the delivery of coin therefrom, said mechanism including a lever member associated with the magazine and a horizontally disposed, transversely rockable, longitudinally movable pin carried by the lever member, an endless carrier, and means operated by the same means for controlling said coin delivery

mechanism to operate said carrier alternately in both directions.

34. In a change making machine, the combination of coin magazines, a series of amount-received-keys, a series of amount-of-purchase-keys, mechanism by which the actual difference between the sum total of the keys of one series depressed and the sum total of the punched keys of the other series is paid out, and semaphores controlled by the coins delivered for visibly indicating the actual change paid.

35. In a change making machine, the combination of a series of coin magazines, mechanism for controlling the delivery from individual of said magazines, said means including lever members associated with each magazine, and horizontally disposed, transversely rockable, longitudinally movable pins carried by said lever members, and means for placing said last-named mechanism in inoperative position by which delivery of the contents of all the magazines may be made simultaneously.

36. In a change making machine, a series of coin magazines, devices controlling the delivery of the coin singly from said magazines, said devices including lever members associated with each magazine, and horizontally disposed, transversely rockable, longitudinally movable pins carried by said lever members and means for placing said devices in inoperative position to allow of the simultaneous emptying of all the magazines.

37. In a change making machine, the combination of a series of coin magazine, said devices including lever members associated with each magazine, and horizontally disposed, transversely rockable, longitudinally movable pins carried by said lever members, devices for controlling the delivery of coin singly from said magazines, selective mechanism operable on said devices, and means for placing all of said devices in inoperative position to allow the simultaneous emptying of all the magazines.

38. In a change making machine, the combination of a series of coin magazines, devices for controlling the delivery of coin singly from said magazines, said devices including lever members associated with each magazine, and horizontally disposed, transversely rockable, longitudinally movable pins carried by said lever members, selective mechanism operable on said devices, a rockable-support for said coin-controlling-devices, and means for actuating said support to allow the simultaneous emptying of all the magazines.

39. In a change making machine, a series of coin magazines, devices controlling the delivery of the coin therefrom, and selective mechanisms operable on said devices, said selective mechanisms including a series of hori-

- zontally disposed transversely rockable pins connected with said coin-controlling-devices, and a universal actuating device corresponding with said pins, an instrumentality for setting said pins in operative relation, and a universal releasing structure for the pins.
40. In a change making machine, a series of coin magazines, devices controlling the 10 delivery of the coins therefrom, selective mechanisms operable on said devices, said selective mechanisms including a series of rockable pins connected with said coin-controlled devices, a series of actuators corresponding with said pins, an actuating lever for operating said actuators, and a spring-actuated-endless draper operable by said actuating lever.
41. In a change making machine, the combination of a series of magazines, devices for controlling the delivery of the coins from said magazines, a universal bar for rendering all said devices inoperative to control the coin, a series of horizontally disposed transversely rockable - pin - members connected with said coin-controlling-devices, a universal actuating device with which said pins are alinable, a setting device for placing said pins initially in alinement with said actuators, selective mechanisms for removing one or more of said pins out of alinement with said actuators, and means to operate the actuating device.
42. In a change making machine, a series of coin magazines, devices for controlling the delivery of the coins from said magazines, a universal bar for rendering all said devices inoperative to control the coin, a series of horizontally disposed transversely rockable - pins connected with said coin-controlling-devices, a universal actuating instrumentality, a setting device for placing said pins in alinement with said actuators, a series of amount-received-keys, a series of amount-of-purchase-keys, and connections between the keys of said several series and respective of said pin-members to carry one or more of said pin-members out of line with their respective actuators.
43. In a change making machine, a series of coin magazines, devices for controlling the delivery of the coins from said magazines, rockable-pins connected with said coin-controlling-devices, a series of actuators, a setting device for placing said pins in line with said actuators, a series of amount-received-keys, a series of amount-of-purchase-keys, connections between the keys of said several series and respective of said pin-members to carry one or more of said pin-members out of line with their respective actuators, latch-members for holding the keys of said several series in depressed position, and a reciprocating bar for tripping said latch-members.
44. In a change making machine, a series of coin magazines, devices for controlling the delivery of the coins from said magazines, rockable-pins connected with said coin-controlling-devices, a series of actuators, a setting device for placing said pins in line with said actuators, a series of amount-received-keys, a series of amount-of-purchase-keys, connections between the keys of said several series and respective of said pin-members to carry one or more of said pin-members out of line with their respective actuators, latch-members for holding the keys of said several series in depressed position, a reciprocating bar for tripping said latch-members, an actuating lever for operating the actuators, and connections between said lever and said tripping-bar.
45. In a change making machine, a series of coin magazines, devices for controlling the delivery of the coins from said magazines, rockable-pins connected with said coin-controlling-devices, a series of actuators, a setting device for placing said pins in line with said actuators, a series of amount - received - keys, a series of amount-of-purchase-keys, connections between the keys of said several series and respective of said pin-members to carry one or more of said pin-members out of line with their respective actuators, latch-members for holding the keys of said several series in depressed position, a reciprocating bar for tripping said latch-members, an actuating lever for operating the actuators, and connections between said lever and said tripping-bar.
46. In a change making machine, a series of coin magazines, devices for controlling the delivery of the coins therefrom, a series of actuators, mechanism operable to place said coin controlling devices in position to be operated by said actuators, selective mechanisms by which only certain of said actuators will operate corresponding of said coin controlling devices, an operating-lever connected with the actuators, a release-bar, and a delivery draper operative by said actuating lever.
47. In a change making machine, a series of coin magazines, devices for controlling the delivery of the coins therefrom, rockable-pins connected with said coin controlling devices, a series of actuators corresponding to said pins, a device for placing said pins in operative position with the actuators, selective mechanisms by which individual of said pins are carried out of operative position with said actuators, an actuating lever for operating the actuators, spring-actuated semaphores operative by the coins delivered from the magazines.

roller connected with the semaphores for re-setting them, an intermittently operable delivery draper, a tripping-bar for releasing the selective mechanisms, and means for operating the tripping bar, the delivery draper and said resetting roller by said actuating lever.

In testimony whereof I have hereunto set my hand in the presence of two subscribing witnesses.

FREDERICK L. NAY.
